UNITED STATES PATENT OFFICE.

ALBERT MUTSCHLER, OF ROCHESTER, NEW YORK.

AUTOMATIC-FEEDING MACHINE-TOOL.

1,218,108.

Specification of Letters Patent.

Patented Mar. 6, 1917.

Application filed December 8, 1915. Serial No. 65,866.

To all whom it may concern:

Be it known that I, ALBERT MUTSCHLER, a citizen of the United States, residing at Rochester, in the county of Monroe and State of New York, have invented certain new and useful Improvements in Automatic-Feeding Machine-Tools, of which the following is a specification.

The object of this invention is to provide a machine that will automatically feed and hold blanks in position for machine operations such as milling, drilling, etc.

This and other objects of the invention will be fully illustrated in the drawings, described in the specification and pointed out in the claims at the end thereof.

In the drawings,

Figure 1 is a top plan view of the machine.

Fig. 2 is a longitudinal section on the line 2^x—2^x of Fig. 1.

Fig. 3 is a vertical section on the line 3^x—3^x of Figs. 1 and 2.

Fig. 4 is an enlarged detail view of the feeding and clamping device.

Fig. 5 is a vertical section through the guide for the feeding device, the section being taken on the line 5^x—5^x of Fig. 4.

Fig. 6 is a vertical section taken through the feeding device on the line 6^x—6^x of Fig. 4.

Fig. 7 is a top plan view of the cam for operating the clamping and milling devices.

Fig. 8 is a section on the line 8^x—8^x of Fig. 3, showing the ratchet feeding device for intermittently advancing the feeding chain.

Fig. 9 is a top plan view of the cam for opening the clamping device.

Fig. 10 is an enlarged detail view of one of the carriers for holding the stock.

Fig. 11 is a perspective view of one of the guides for positioning and holding the stock in an upright position with reference to the carrier.

Fig. 12 is a perspective view of the piece of the finished stock on which this machine is adapted to operate.

Fig. 13 is a longitudinal section through one of the pockets and guides.

In the accompanying drawings like reference numerals indicate like parts.

In the drawings letter A indicates the main frame and reference numeral 1 indicates the power shaft mounted thereon, on which shaft is mounted the pulley 2 which

is driven by a belt. On this shaft is keyed a worm 3 which engages with and drives the worm wheel 4, keyed to the shaft 5. The shaft 5 and parts associated therewith are carried below the auxiliary frame 48. On this shaft are carried the cam wheels 6, 7 and 8 fastened thereto by set screws. Also positively fastened to the shaft is the gear wheel 9 which meshes with the gear wheel 10, mounted to rotate on a stud 11 carried on a bracket 12 which is integral with the frame of the machine. On the gear wheel 10 is a crank pin 13 with which engages a connecting rod 14, which connecting rod, at its forward end, engages with a crank 15 which is mounted to rock on the shaft 16 supported in the frame of the machine. On this shaft is loosely mounted the sprocket wheel 17 to which is rigidly fastened the ratchet wheel 18. On the crank 15 is provided a boss in which is mounted to slide radially a spring pressed pawl 19, which pawl rides over the ratchet wheel when the connecting rod 14 is moved to the right in Fig. 3 and engages the ratchet wheel and causes the rotation thereof and that of the sprocket wheel 17. The connecting rod is provided with an adjustment 20 by which it may be lengthened or shortened and by this adjustment the position in which the crank 15 is left at the end of the stroke may be varied. This in turn effects the position in which the stock is placed during the cutting or the milling operation.

On the opposite end of the frame is carried a shaft 21 on which is mounted to rotate a sprocket wheel 22. Over the sprocket wheels 17 and 22 travels the sprocket chain 23. This sprocket chain is what is ordinarily known as a carrier chain, on certain links of which are carried brackets 24. Attached to these brackets by screws (shown in Fig. 1) are the carriers 25 which carriers are recessed at 26 to receive the brackets. As shown in Fig. 3 two consecutive links are provided with brackets and guide frames and the preceding and the following link is left blank. This arrangement, however, can be varied within considerable limits. As will presently be explained, the mills or cutters on this machine are preferably worked in pairs and the machine is therefore arranged so that two pieces of stock can be carried together and worked on at the same time. The carrier 25 consists of a block in which a dove tailed slot 27 is

cut in which is mounted the slide 28. On the carrier is mounted and secured thereto by screws (Fig. 1) the holder 29 in which is formed a circular opening 30 with a shoulder 31 at the bottom thereof closing half of said opening. Into this holder may be set the piece of stock 32 shown in Fig. 12, which, in this case, is intended to form part of a hinge used to join the parts of a shoe last. The half round opening at the bottom of the pocket serves to hold the stock so that it will be promptly positioned to be locked in place as will now be described.

The piece 32 is round or cylindrical and one half of its thickness is cut away at the bottom forming a flat bearing surface 33 thereon which is perforated at 34. The shape of the holder is such that the pin is held with this perforation extending longitudinally of the slide. The slide 28 is formed at one end with a cam 35 and at the other end with a pin block 36 having a pin 37 integral therewith. The slide 28 is adapted to move to the right from the position shown in Fig. 13 to engage the pin 37 with the opening 34 in the stock 32 and lock it in the holder 29. This operation of the slide 28 is secured as follows:

On each end of the carrier 25 is formed the projecting lips 38 and 39 which are adapted to engage with the grooves 40 and 41 formed in the frame of the machine, along which the carrier frames are adapted to travel as they are drawn by the sprocket 35 chain.

On top of the frame of the machine is provided the bars 42 and 43, on top of which in turn are carried the plates 44 and 45, which plates project toward each other, an opening being left between them through which the piece of stock 32 can travel as it is carried along by the chain. Under this slot travels the holder 29 so that when the stock is positioned therein it will travel along the slot. Fastened to the under side of the plate 45 is the cam 46 having a beveled edge 46' at each end thereof which engages with the cam 35 carried on the slide and by which the slide is moved from the position shown in Fig. 13 to the position shown in Fig. 10 and by this movement the pin 37 engages with the opening 34 in the stock 32 and locks it in place. The plate 44 may, if desired, be omitted. The bars 42 and 43 may be cast integral with the frame instead of being separately added thereto.

The stock is locked in position by the forward movement of the chain, the movement of the chain being from the left to the right in Fig. 4, the cam 46 being stationary with the frame and the cam 35 moving with the chain. As will be seen in Fig. 4 the cam 46 extends from one side past the middle of the machine to a considerable distance on the opposite side and during the travel of the

guide frame and slide past this cam the stock will be held locked in position. Where the cam 46 ends the cam 47 begins and this cam operates on the opposite side of the cam 35 and moves it in the reverse direction, disengaging the pin 37 from the stock and moving it to the position shown in Fig. 13.

While the stock is traveling intermittently along the cam 46 it is operated on by the mills or cutters and is stopped at a predetermined position for this purpose. This operation of the mills will now be described.

Mounted transversely of the machine is the auxiliary frame 48 on which are mounted to slide the two heads 61 and 62. On the head 61 are mounted to rotate the two shafts 51 and 52 and on the head 62 are mounted to rotate the shafts 49 and 50. On each of these shafts is carried a spiral gear. Mounted transversely of these shafts are the shafts 53 and 54, 55 and 56 on which are also carried spiral gears, each of which spiral gears meshes with the spiral gears on the transverse shafts therebelow. Pulleys 57, 58, 59 and 60 are provided by which these several shafts may be driven.

On the inner ends of the shafts 49, 50, 51 and 52 are provided the milling cutters 63, 64, 65 and 66, which cutters are adapted to work on the opposite sides of two pieces of stock as the heads 61 and 62 are brought together for this purpose.

Clamps are provided on the main frame A which clamp the stock between them before the cutters operate on the stock and the mechanism by which the clamps and the cutters are moved forward and back will now be described.

The cam wheel 6 carries thereon the cams 67, 68 and 69. Mounted in the main frame A and passing through the transverse frame 48 is the shaft 70, on the bottom of which is carried the crank 71 having a crank pin 72 at the end thereof with an antifriction roller 73 mounted to rotate thereon. This crank pin 72 is engaged by the cam 67 which causes the crank 71 to swing to a predetermined position and is held in that position while the cam is passing it. On top of the shaft 70 is an eccentric or cam 74 which engages with the vise jaw 75.

On the cam wheel 8 is placed a similar cam 67 which engages with a similar crank 71, shaft 70, eccentric 74 and jaw 75 and as the cams 67 rotate in unison the jaws operated thereby will move together simultaneously, pinching the stock between them. Immediately after the stock is pinched or fastened in place the cams 68 operate to advance the mills as will now be described.

On the head 61 is carried a pin 76 which projects into the slot 77 in the transverse frame 48. This pin is round with flat sides and is shouldered at both ends, the one end being threaded and being fastened in place

by the nut 78 and the other end carrying the antifriction roller 79 which engages the cam 68. As the cam wheel rotates it first operates the jaws through the cam 67 to clamp 5 the stock in place and immediately thereafter the cam 68 operates through the pin 76 to push the head 61 forward and with it the mills or cutters that operate to cut the stock. Similar cams oppositely placed are 10 carried upon the cam wheels 8 and engage with the pin 76 to drive the head 62 forward, causing the stock to be cut on the opposite side at the same time. After the cutting operation of the mills is completed the cams 69 15 on the cam wheels 6 and 8 operate on the pins 76 to draw the heads 61 and 62 back, after which the cam 80 on the cam wheels 7 operates on the antifriction rollers 81 of the cranks 71 to rock them in the opposite 20 direction, releasing the jaws 75 which are then drawn in the reverse direction by the springs 82.

To limit the movement of the heads 61 and 62, adjusting screws 83 are provided 25 which travel therewith and make contact with the cross frame, limiting the movement of the heads and the movement of the cutters carried thereby.

After the operation of the cutters is completed 30 the intermittent travel of the chain carries the carriers past the cam 46 and to the cam 47. The cam 47 then acts upon the cam 35 to move the slide in the opposite direction and disengages the pin 37 from 35 the stock. As the chain continues to travel intermittently the guide frame and its slide will travel around the sprocket wheel and become inverted and while inverted the stock is dropped from the pocket or at any 40 time it may be blown therefrom by a blast of air or an equivalent device.

The operation of my machine is as follows:

The pulley 2 will be driven continuously 45 and the chain will be fed intermittently as above described, and a piece of stock is placed in each pocket by the attendant of the machine. The intermittent feeding of the chain will bring the guide frame and 50 slides successively first into contact with the cam 46 by which the stock which had been previously placed in the holder, will be locked in position and will be advanced by successive steps until it is positioned before 55 the cutters, at which point the continuously rotating cam wheels 6 and 8 will first cause the stock to be clamped in place and will then advance the cutters to operate thereon, after which the cutters will be withdrawn 60 and the jaws of the clamp will also be withdrawn, after which the stock is again advanced until the cam 47 operates to release the stock, after which it can be removed from the machine by hand or by 65 gravity or in any other suitable way.

Instead of the milling cutters that are illustrated, other tools may be used so that a variety of operations may be performed by the machine. If drills are used they would be placed in one head only and omitted 70 from the other head or the other head may be omitted altogether.

I claim:

1. In a machine tool the combination of an endless conveyer, a carrier attached thereto capable of holding stock therein, a stationary cam placed in the path of said carrier for operating and closing said carrier to lock the stock therein as it is advanced, means for intermittently advancing said carrier, means for clamping said stock independently of its carrier, and means for cutting said stock while it is so clamped. 75

2. In a machine tool a movable carrier for stock comprising a block having a slot 80 therein, a slide mounted in said slot, a holder mounted on said block, said slide being mounted to move under said holder and engage the work therein. 85

3. In a machine tool a movable carrier 90 for stock comprising a block having a slot therein, a slide mounted in said slot, a holder mounted on said block, said slide being mounted to move under said holder and a cam on said slide, a stationary cam 95 engaging said cam on said slide by which it is moved under said holder to engage the work therein. 95

4. In a machine tool a movable carrier for stock having a holder mounted thereon 100 having an opening therein, said holder having a shoulder in the bottom thereof partially closing said opening, said shoulder being adapted to engage the stock and to hold it in position in the holder and permit it 105 to extend below the holder. 105

5. In a machine tool the combination of a frame, a conveyer traveling thereon, carriers on said conveyer capable of holding stock therein, an auxiliary frame transverse 110 thereto having a rotating shaft thereon, three cams mounted to rotate with said shaft, a pair of jaws mounted on the main frame, an eccentric for moving each jaw, a shaft for each eccentric, and cranks on the 115 end of each shaft, said cams engaging with said cranks to close the jaws on the stock and hold it and then open the jaws and release said stock. 115

6. In a machine tool a carrier for stock 120 comprising a block having a slot therein, a slide mounted therein, a block on said slide at one end thereof, a pin on said block projecting inwardly therefrom, a cam on the opposite end of said slide by which said slide 125 is moved. 125

7. In a machine tool the combination of a frame, a rotating cutter mounted to slide on said frame, a carrier mounted to move transversely to the movement of said cutter, 130 180

4
said carrier providing a holder having a locking dog mounted to slide at the bottom thereof to lock the stock in place in said holder.

5 8. In a machine tool the combination of a frame, a rotating cutter mounted to slide on said frame, a carrier mounted to slide transversely to the movement of said cutter, said carrier providing a holder having a 10 locking dog mounted to slide at the bottom thereof to lock the stock in place in said holder, means to move said locking dog and lock the stock in said holder before it reaches said rotating cutter and means for automatically releasing the stock from said holder

after it has been worked upon by said rotating cutter.

9. In a machine tool the combination of a frame, a rotating cutter mounted to slide on said frame, a carrier mounted to move 20 transversely to the movement of said cutter, said carrier providing a holder having a locking dog mounted to slide at the bottom thereof to lock the stock in place in said holder, driving means for said carrier to 25 intermittently move said carrier in front of said rotating cutter.

In testimony whereof I affix my signature.

ALBERT MUTSCHLER.
